US00D470847S

(12) **United States Design Patent** (10) Patent No.: **US D470,847 S**
(45) Date of Patent: **** Feb. 25, 2003**

(54) **HANDHELD INTERROGATOR**

(75) Inventors: **Casey L. Carlson**, Edina, MN (US); **Peter M. Eisenberg**, Minneapolis, MN (US); **Bernard A. Gonzalez**, St. Paul, MN (US); **Paul A. Sevcik**, Birchwood, MN (US); **Jonathan P. Van Dore**, Minneapolis, MN (US)

(73) Assignee: **3M Innovative Properties Co.**, St. Paul, MN (US)

(**) Term: **14 Years**

(21) Appl. No.: **29/158,994**

(22) Filed: **Apr. 12, 2002**

(51) LOC (7) Cl. **14-02**

(52) U.S. Cl. **D14/428**

(58) Field of Search D10/78, 104; D14/428; D19/41-51; 235/382, 375, 378, 385, 454, 462.15, 472.02, 462.46, 486, 380; 340/10, 572.4, 572.3, 572.6, 572.7, 505, 825.34; 382/312-315, 318, 319, 321; 250/203.1, 216; 705/28

(57) **CLAIM**

The ornamental design for a handheld interrogator, as shown and described.

DESCRIPTION

FIG. 1 is a perspective view of the handheld interrogator showing our new design;

FIG. 2 is a front elevational view thereof;

FIG. 3 is a back elevational view thereof;

FIG. 4 is a top plan view thereof;

FIG. 5 is a bottom elevational view thereof;

FIG. 6 is a right side elevational view thereof; and,

FIG. 7 is a left side elevational view thereof.

The broken line drawing in all figure views is for illustrative purposes only, and forms no part of the claimed design.

UNITED STATES PATENT AND TRADEMARK OFFICE
CERTIFICATE OF CORRECTION

PATENT NO. : Des. 470,847 S
DATED : February 25, 2003
INVENTOR(S) : Carlson, Casey L.

Page 1 of 1

It is certified that error appears in the above-identified patent and that said Letters Patent is hereby corrected as shown below:

Title page,

Before Item [56], insert the following paragraph:

-- Government License Rights

This invention was made with Government support under Agreement No. NMA202-97-9-1050 awarded by the National Imagery and Mapping Agency. The Government has certain rights in the invention. --

Signed and Sealed this

Twenty-first Day of September, 2004

JON W. DUDAS
Director of the United States Patent and Trademark Office
